UNITED STATES PATENT OFFICE.

JOHN BOECK, OF BOISE, IDAHO.

TURNING AND STOPPING SIGNAL FOR AUTOMOBILES.

1,211,279.

Specification of Letters Patent. Patented Jan. 2, 1917.

Application filed June 22, 1916. Serial No. 105,308.

To all whom it may concern:

Be it known that I, JOHN BOECK, a citizen of the United States, residing at Boise, in the county of Ada and State of Idaho, have 5 invented certain new and useful Improvements in Turning and Stopping Signals for Automobiles; and I do declare the following to be a full, clear and exact description of the invention, such as will enable others 10 skilled in the art to which it appertains to make and use the same.

This invention is a signal for application to automobiles, to be projected from one 15 side of the car when turning corners or when stopping, to notify the drivers of other vehicles that a stop or turn is to be made, the device therefore obviating the necessity of the chauffeur using his hand as a signal.

The principal object of the invention is to 20 provide a device of the class described which may be simply and inexpensively manufactured and marketed, yet one which regardless of these advantages, will be highly efficient both by day and night.

With the foregoing general object in view, 25 the invention resides in certain novel features of construction and in unique combinations of parts to be hereinafter fully described and claimed, the descriptive matter 30 being supplemented by the accompanying drawings which constitute a part of this application and in which:

Figures 1 and 2 are elevations of the opposite sides of the improved signal, the same 35 being shown applied to a wind shield in Fig. 1; Fig. 3 is a side elevation looking in a direction at right angles to Figs. 1 and 2; Fig. 4 is an enlarged vertical section with the parts in normal position; Fig. 5 is a 40 similar view with said parts in operative position; and Fig. 6 is a horizontal section on the plane of the line 6—6 of Fig. 5.

In specifically describing the structure shown in the drawings above briefly described, similar characters will be employed to designate corresponding parts throughout the several views and reference will be herein made to the numerous elements by their respective indices. To this end, the 50 numeral 1 designates an elongated casing which is open at one side and is provided at the upper end of this side with a hood 2. A spring wound roller 3 is confined in the casing 1 and a signaling flag 4 preferably 55 of red or other highly colored material, is wound on said roller. An operating rod 5

passes slidably through the lower end of the casing 1 and is provided at its outer end with a lateral branch 6 preferably formed by bending said rod, said branch being disposed at the open side of the casing and being secured to the free end of the flag 4. By this construction it will be obvious that when the rod 5 is projected, the flag will be unfurled, whereas when said rod is released, 60 the spring 7 of the roller 3 will rotate said roller to rewind the flag, thus simultaneously returning the rod 5 to its normal retracted position.

For holding the rod 5 when projected, a 70 catch is provided, said catch being preferably in the form of a hook 8 connected to the casing and adapted to automatically engage an ear or the like 9 on the aforesaid rod when the latter is forced outwardly. 75 As indicated on the drawings, a spring 10 is provided for applying the hook 8, and the latter may be released manually at will.

A lamp bracket 11 is secured to the branch 80 6, said bracket carrying a socket 12, a lamp 13 being mounted in said socket. A wire 14 is electrically connected to the casing 1 in any suitable manner, and through the instrumentality of the numerous metallic parts of the device, supplies current to one 85 terminal of the lamp 13 through the socket 12 in the usual manner, an additional wire 15 being provided for conducting current from the other terminal of said lamp. The wire 15 is disposed between two plies 16 of 90 which the flag 4 is constructed, said plies being preferably quilted together as indicated at 17, and the inner end of said wire 15 is electrically connected with a metallic band 18 which surrounds but is insulated 95 from the roller 3. The band 18 constitutes a relatively fixed contact member to be engaged by a movable contact member 19 which is adapted to be projected to operative position when the rod 5 is forced outwardly, thereby completing the circuit of 100 the lamp 13 to illuminate the latter.

The movable member 19 preferably includes a tube 20 slidably horizontally through an auxiliary casing 21 at the lower 105 end of the casing 1, said tube carrying on its inner end an insulating block 22 to which a contact plate 23 is secured by screws 24 or other suitable means, this plate being electrically connected to one end of an insulated 110 current conducting wire 25 which will be secured to one terminal of a source of elec-

tric current, while the wire 14 will be connected to the other terminal thereof. As shown clearly in Figs. 4 and 5, the end of the tube 20 is preferably threaded into the block 22 and said end is also threaded through a plate 26, this plate, the block 22 and the plate 23 being all disposed in the main casing 1. Parallel rods 27, however, project from the plate 26 into the auxiliary casing 21 and carry cross heads 28 on their free ends, said cross heads preferably having apertures in order that they may travel on guide rods 29. Springs 30 bear against the heads 28 to normally retract the entire member 19 to dispose the plate 23 out of contact with the band 18.

For projecting the member 19 when rod 5 is forced outwardly, a bracket or other suitable lateral projection 31 will be carried on the inner end of said rod to be forced into contact with the outer end of tube 20 when said rod is projected. This will move the plate 23 into contact with the band 18 and will thus complete the circuit of the lamp 13, which by this time has been projected together with the flag 4. The hook 8 now comes into operation to hold the parts in their operative positions until released manually.

30 The tube 20 serves not only as projecting means for the contact plate 24, but as a housing for the wire 25, the free end of said tube being preferably equipped with an up-standing cylindrical hood 32 through whose lower end said wire projects, this hood also receiving the thrust of the projection 31.

The device constructed substantially as shown and described, may be secured to any preferred part of an automobile, but for 40 illustrative purposes the casing 1 is shown equipped with a pair of clamps 33 which are shown in Fig. 1 as gripping one side of a wind shield S. Regardless of its application, the device will be highly efficient and 45 durable and will fulfil a long felt need, it being obvious that in day light the flag 3 will serve as the warning, whereas at night the lamp 13 may be readily seen, and this lamp will partially illuminate the flag 4 to 50 render the same visible. It is to be of course understood that any suitable switch may be

provided for breaking the circuit of lamp 13, when its use is not required.

In the foregoing I have described certain specific details for accomplishing probably 55 the best results and in the accompanying drawings such details have been illustrated, but it is to be understood that the drawings are merely for illustrative purposes and that within the scope of the invention as claimed 60 numerous changes may be made without sacrificing the main advantages of the invention:

I claim:

1. In a turning and stopping signal for 65 automobiles, the combination of a spring wound roller, a signal flag wound thereon, an operating rod slidable transversely of said roller and secured at its outer end to the free end of said flag for unfurling the 70 same at will, an electric signal lamp carried by said outer end of the rod, a circular contact on the roller and a relatively movable contact for closing the circuit of said lamp, and means on the operating rod for forcing 75 said relatively movable contact against the circular contact when said rod is projected.

2. In a turning and stopping signal for automobiles, the combination of a spring wound roller, a signal flag wound thereon, 80 an operating rod slidable transversely of said roller and secured at its outer end to the free end of said flag for unfurling the same at will, an electric signal lamp carried by said outer end of the rod, wiring for said 85 lamp including a wire extending along the flag, a circular contact to which said wire is secured, said contact being mounted on one end of the roller, a spring retracted member having a contact to be forced 90 against said circular contact, and a lateral projection on the operating rod for striking and projecting said member when said rod is projected.

In testimony whereof I have hereunto set 95 my hand in the presence of two subscribing witnesses.

JOHN BOECK.
